CORD LOCK FOR VENETIAN BLINDS

Davis J. Ajouelo, Atlanta, Ga., assignor to Armand
May, Atlanta, Ga.

Application November 7, 1938, Serial No. 239,388

3 Claims. (Cl. 156—17)

This invention relates to improvements in cord locks for Venetian blind constructions.

The primary object is to provide a novel locking mechanism for releasably securing the cord by which the slats of the blind are raised and lowered, the locking mechanism being operative by frictional engagement therewith of the cord as the slats are lowered to releasably clamp the cord between a locking roller and the wall of a bracket in which said roller is pivoted.

In this connection, the invention also contemplates a bracket or housing for supporting the locking mechanism, which bracket or housing is so constructed that the lifting cord can be inserted in a passage between the locking roller and the cooperating clamping wall of the bracket by a sidewise or lateral movement of the cord. Thus, the lifting cord can be assembled without the necessity of threading it endwise through the instrumentalities with which it is associated or cooperates.

With these and other objects in view, the invention consists in certain details of construction and combinations and arrangements of parts, all as will hereinafter be more fully described, and the novel features thereof particularly pointed out in the appended claims.

In the accompanying drawings, illustrating the preferred embodiment of the present invention—

Figure 1 is a front elevational view of a blind, the intermediate portions of the slats and rails having been broken out;

Fig. 2 is a sectional view on the line 2—2 of Fig. 1;

Fig. 3 is a sectional view on the line 3—3 of Fig. 2;

Fig. 4 is a detail perspective view of the housing or bracket with the lift-cord-locking roller pivoted therein; and

Fig. 5 is a plan view of the blank from which the bracket or housing for the locking mechanism is formed.

As usual, the blind consists of a number of slats 20, suitably attached to suspension tapes 21, which, in turn, are secured to the base rail 22 and the combined head and tilt rail 23. To properly position the tapes 21 with respect to the rail, a plate or clip 25 is provided, said plate having slots 26 in each end thereof through which the tapes extend. Similar plates 25 are also provided for positioning the tapes with respect to the head and tilt rail 23.

The combined head and tilt rail 23 is of a

construction corresponding to the base rail 22, but this head and tilt rail is provided at its extremities with trunnions, whereby it may be rotated to effect a tilting of the slats. Preferably, a plate 29 is attached to each end portion of rail 23, and these plates carry the trunnions 30, 31. Trunnion 30 is supported in the bracket 33. At the exterior of the bracket the protruding end of a shaft 36 is provided with a pulley 37, over which the tilting cord 38 runs or extends. If desired, a leaf spring 40 may be provided to insure retention of the tilting cord in the groove of pulley 37.

As is also customary, a pull cord looped at its intermediate portion, as illustrated at 41, extends along the head and tilt rail 23 and downwardly through the slats 20 with its ends secured to the base rail for the purpose of permitting the base rail and the slats to be raised and lowered as desired. The weight of the base rail and slats is such that they normally tend to move downwardly by gravity and, for this reason, it is necessary that means be provided for locking or clamping the cord 41 in order that the base rail and slats can be releasably positioned at the desired elevation. For this purpose, at the end of the head and tilt rail opposite the tilting mechanism previously described, there is a bracket 42 housing a locking mechanism and having there-in a bearing for the trunnion 31. Within this bracket, the pull cord 41 passes around a guide sleeve 43 rotatable on a pin 44 secured in two opposite walls of the bracket. Also pivoted in said bracket is a clamping roller 45. Roller 45 is rotatable on a pin 46, the pin being disposed eccentrically of the roller and the surface of the roller is knurled or roughened so that, if the pull cord 41 is pressed against the surface of the eccentrically mounted roller, while the slats and head rail are being lowered, the frictional engagement of the cord with the roller will rotate the latter with the result that the surface of the roller will be advanced toward the wall 47 of the bracket, ultimately gripping the cord between said wall and its surface. In other words, the roller 45, with its eccentric mounting, has a camming action as the pull cord 41 moves upwardly during downward movement of the base rail and slats. If desired, the wall 47 of the bracket, which cooperates with this cam roller 45, may take the form of a spring finger bent up somewhat from the wall proper of the bracket, as more particularly shown in Figs. 3 and 4.

This bracket for the locking mechanism and

trunnion 31 is also stamped or formed-up from a single blank of metal, such as is illustrated in Fig. 5. By bending the blank along lines C, in Fig. 5, the two opposite walls 42^a, 42^b, are formed the wall 42^a being slotted as at 48 to form a bearing for the trunnion 31 and the wall 42^b being formed with apertures for attachment of the bracket to a clip by which it is mounted in the window opening. By bending the blank along the line D, the portion 42^c forms a wall having apertures 49 therein for the pins 44, 46, and by bending the blank along the line E, the portion 42^d is disposed opposite the bent-up portion 42^c, so that the openings 49^a are arranged in registry or alignment with the holes 49 to receive pins 44, 46.

Referring particularly to Fig. 4, it will be noted that the wall 42^b, comprising the cord-engaging portion 47, terminates somewhat short of the wall 20 42^d of the bracket 42, in which the lifting-cord-locking-cam roller is mounted. Thus, there is a slot formed between the extremities of these two walls or in one of the side walls of the bracket, through which the lifting cord can be inserted 25 sidewise into the space in which it is normally disposed or between the eccentric cam roller 45 and the cord-engaging surface 47 of the wall. Here, again, endwise threading of the cord ends

through the locking mechanism is eliminated in the same way that threading of the cord through the tilting mechanism is obviated.

What I claim is:

1. In a lock mechanism for cords, a housing, a cam member supported in said housing, there being a cord passage between the surface of the cam and a wall of the housing, said cam being movable toward said wall to press cords in the passage toward the wall, and means on said wall 10 yieldingly resisting the cords pressed against the same by the cam.
2. In a lock mechanism for cords, a housing, a cam member supported in the housing, there being a cord passage between the cam and one 15 wall of the housing, and a spring member formed on said wall engageable with a cord in said passage.
3. In a lock mechanism for cords, a housing, a cam member supported in the housing, there 20 being a cord passage between the cam and one wall of the housing, and a spring on said wall engageable with a cord in said passage, there being an entrance opening between said wall and an adjacent wall of the housing for the 25 lateral insertion and removal of a cord into and out of said passage.

DAVIS J. AJOUVELO.
